X-RAY COLLIMATING EXTENSION TUBE POSITIONING RING FOR POSTERIOR TYPE DENTAL X-RAY FILM HOLDERS

Charles F. Stevenson, Elgin, Ill., assignor to Rinn Corporation, Elgin, Ill.

Filed Apr. 18, 1974, Ser. No. 461,951

Term of patent 14 years

Int. Cl. D24—01

U.S. Cl. D83—1 H

FIG. 1 is a perspective view of an X-ray collimating extension tube positioning ring for posterior type dental X-ray film holders showing my new design;

FIG. 2 is a plan view of the positioning ring taken from the side of same shown in FIG. 1;

FIG. 3 is a plan view of the positioning ring taken from the far side of the ring as shown in FIG. 1;

FIG. 4 is an edge plan view of the positioning ring taken substantially along line 4—4 of FIG. 1;

FIG. 5 is an edge plan view of the positioning ring taken substantially along line 5—5 of FIG. 3;

FIG. 6 is an edge plan view of the positioning ring taken substantially along line 6—6 of FIG. 2;

FIG. 7 is a fragmentary view in plan taken substantially along line 7—7 of FIG. 1; and

FIG. 8 is a fragmentary sectional view taken substantially along line 8—8 of FIG. 2.

I claim:

The ornamental design for an X-ray collimating extension tube positioning ring for posterior type dental X-ray film holders, substantially as shown.
